COLLAR SUPPORT

Filed May 19, 1931

UNITED STATES PATENT OFFICE

PAUL E. ALEXANDER, OF TAKOMA PARK, MARYLAND

COLLAR SUPPORT

Application filed May 19, 1931. Serial No. 538,542.

The invention relates to a new and improved device for use by launderers and manufacturers of gentlemen's shirts with attached collars, for the purpose of insuring delivery of the shirt with its collar in perfect condition.

It is customary to delivery the finished shirts boxed or wrapped and pinned upon laundry boards, often with no support for the collars but frequently with strips of cardboard so placed as to attempt to hold the collars in proper shape. Such prior supports however have proven to be entirely inadequate for the intended purpose, with the result that the collars become badly wrinkled or creased.

The object of my invention has been to provide a greatly improved yet an inexpensive support which may be quickly and easily inserted without danger of breakage and will effectively support the collar in the shape which it assumes when being worn, even if an unusually large number of the shirts be packed one upon another.

With the foregoing in view, the invention resides in the novel subject matter herein-after described and claimed, description being accomplished by reference to the accompanying drawing.

Fig. 1 is a perspective view showing a shirt with attached collar secured upon the conventional laundry board in readiness for delivery, the collar being held in perfect shape by one of the improved supports.

Fig. 2 is a perspective view more or less exaggerated and illustrating the simple manner of inserting the support between the inner and outer walls of the collar.

Fig. 3 is a detail sectional view on line 3-3 of Fig. 2, illustrating the manner in which the support holds all portions of the collar except the points, perpendicular to the bosom and allows said points to take the same positions which they occupy when the shirt is being worn.

Fig. 4 is a perspective view of one of the supports.

Fig. 5 is a detail sectional view partly in elevation, illustrating the manner in which a number of the shirts provided with the sup-

ports, may be boxed without danger of wrinkling or creasing the collars or the bosoms.

The invention is formed from a single strip 6 of "glazed" or "unglazed" cardboard, fibre board or any other material much stiffer than the conventional shirt collar and having a sufficient degree of stiffness to adequately sustain any reasonable amount of weight or pressure when standing on edge. The strip 6 is adapted for insertion between the inner and outer walls 7 and 8 of the collar and is of a length to extend substantially throughout the front half of the circumference of said collar. This strip is provided with a straight upper edge 9 for reception in the crease 10 at the upper edge of the collar, and said strip edge 9 is unidirectional throughout its length. The lower edge 11 of the strip 6 is adapted to rest upon the shirt substantially at the base of the inner collar wall 7, and said strip is provided with a vertically elongated notch 12 centrally disposed and opening through said lower edge 11, said notch being adapted to engage the usual collar button 13 which is permanently attached to the shirt collar. The end portions of the strip 6 are cut away in part, preferably by forming them with relatively large notches 14 which open through the lower edge 11 of said strip, thereby so weakening said end portions as to allow them to be easily twisted as illustrated in Fig. 2 when inserting and removing the support.

In applying the device, it is positioned in front of the collar with the collar points raised somewhat if necessary, the strip being pushed downwardly to snugly seat behind the button 13. Then, with one hand, one point of the collar is swung upwardly (not necessarily to such an extent as illustrated in Fig. 2) and with the other hand, one end portion of the strip is slid under the outer collar wall 8 and upwardly between the two walls 7 and 8, the weakening of the strip allowing it to readily twist without breakage during such insertion. The other point of the collar is now similarly raised and the other end of the strip is inserted in the same way. The inserted strip stands sub-

stantially perpendicular to the shirt bosom and the laundry board B upon which the shirt is secured, as seen in Figs. 1 and 3, the upper edge 9 of the strip holding the upper edge or crease 10 of the collar in a plane substantially parallel with the shirt bosom. The lower edge of the strip then rests solidly upon the shirt and hence the collar is held in proper shape. With the collar in this supported condition, it will sustain a great amount of weight or downward pressure without becoming wrinkled or otherwise unshapely, and it will be seen that the points of the collar lie orderly in such positions that there is no danger of them becoming distorted. The entire collar is supported in the shape which it assumes when the shirt is being worn and hence ill-fitting is overcome.

When packing a number of the shirts in a box or package, they may be placed as diagrammatically illustrated in Fig. 5, the properly supported collars insuring that the shirt bosoms shall not contact with each other with danger of becoming wrinkled.

I am familiar with a device which has heretofore been quite extensively used, said device consisting of a V-shaped strip of cardboard inserted between the inner and outer walls of the collar and having a notch to engage the collar button. It is difficult however to apply this support without breakage thereof and without spoiling the appearance of the collar. Then too, the device in question remains flat in use, necessitating that the collar also shall lie flat, producing objectionable creases extending vertically from the shoulders of the shirt. The present invention however, supports the collar in the form which it assumes when the shirt is being worn, it is easily applied and removed without danger of breakage, and its use does not form any vertical creases upon the collar. To remove the device, first one end and then the other thereof is gripped and pulled outwardly and twisted simultaneously, causing it to readily slide out below the outer wall without any danger of impairing the shape and appearance of the latter. Then, the strip is upwardly pulled from the button 13. It is preferable that the strip be of such height that its ends will be accessible below the edge of the collar as seen in Fig. 1, facilitating removal.

Excellent results have been obtained from the specific construction shown and such construction may therefore be followed. However, within the scope of the invention as claimed, minor variations may be made, and should it be desired, the device may be inserted upwardly in inverted position.

I claim:

1. A device for supporting an attached collar of a shirt when the latter is secured upon a laundry board for delivery, comprising a one-piece strip of relatively stiff material

adapted for reception between the inner and outer walls of the collar and having a straight upper edge extending uni-directionally throughout its length for reception in the crease at the upper edge of the collar, said strip being provided with a lower edge adapted to rest upon the shirt substantially at the base of said inner wall to support said strip substantially perpendicular to the board-carried shirt, said strip being of a length to extend only throughout substantially the front half of the collar and having a substantially central downwardly open notch to receive the usual collar button of the shirt.

2. A device for supporting an attached collar of a shirt when the latter is secured upon a laundry board for delivery, comprising a one-piece strip of relatively stiff material adapted for reception between the inner and outer walls of the collar and having a straight upper edge extending unidirectionally throughout its length for reception in the crease at the upper edge of the collar, said strip being provided with a lower edge adapted to rest upon the shirt substantially at the base of said outer wall to support said strip substantially perpendicular to the board-carried shirt, said strip being adapted to extend throughout substantially the front half of the circumference of the collar and having a substantially central downwardly open notch to receive the usual collar button of the shirt, the end portions of said strip between said central notch and the strip ends being weakened to allow twisting of said end portions incident to inserting them between the inner and outer collar walls.

3. A device for supporting an attached collar of a shirt when the latter is secured upon a laundry board for delivery, comprising a one-piece strip of relatively stiff material adapted for reception between the inner and outer walls of the collar and having a straight upper edge extending unidirectionally throughout its length for reception in the crease at the upper edge of the collar, said strip being provided with a lower edge adapted to rest upon the shirt substantially at the base of said outer wall to support said strip substantially perpendicular to the board-carried shirt, said strip being adapted to extend throughout substantially the front half of the circumference of the collar and having a substantially central downwardly open notch to receive the usual collar button of the shirt, the end portions of said strip between said central notch and the strip ends having additional relatively large notches in the lower edge of the strip, said notches so weakening said end portions as to allow easy twisting thereof without breakage when inserting said end portions between the inner and outer collar walls.

4. In combination with a laundry board,

and a laundered shirt secured on said board and having an attached collar provided with the usual collar button; a one-piece strip of relatively stiff material between the inner 5 and outer walls of said collar and resting upon the shirt substantially at the base of said inner wall, said strip being perpendicular to said laundry board, extending only throughout substantially the front half of the 10 collar and having its upper edge disposed in and in contact with the crease at the upper edge of the collar, said strip being provided with a central vertical notch receiving the usual attaching means of said collar button.

15 In testimony whereof I affix my signature.
PAUL E. ALEXANDER.
